UNITED STATES PATENT OFFICE

2,524,272

DIRECT GAS-FIRED OVEN

Albert M. Sage, Belleville, N. J., assignor to
Steiner-Ives Co., Newark, N. J., a corporation
of New Jersey

Application August 22, 1946, Serial No. 692,177

3 Claims. (Cl. 263—19)

1

This invention relates to heating devices.

An object of the invention is to provide a high humidity heat generator for the heat treatment of objects in an oven or the like.

Another object of the invention is to provide a direct gas fired high humidity heat generator whereby high humidity and comparatively high temperatures can be obtained without creating excess steam pressure.

A further object of the invention is to provide a gun type burner firing a flame into a water jacketed combustion chamber, in which steam thus created in the water jacket is fed into the combustion chamber by passing the same through the flame to be heated thereby and then circulated through an oven or the like.

Still another object of the invention is to provide a heat generator of the type specified, which is adaptable to numerous uses, is simple in design, and highly effective in operation.

Other objects and advantages of the invention will become apparent from the following description of a preferred embodiment thereof as illustrated in the accompanying drawings, and in which,

Figure 1 is a longitudinal sectional view of a heat generator according to the invention, shown installed in an oven;

Figure 2 is a transverse sectional view taken on line 2—2 of Figure 1;

Figure 3 is an enlarged longitudinal sectional view of the heat generator shown in Figure 1, but apart from the oven, and with parts broken away to disclose the interior construction;

Figure 4 is a transverse sectional view taken on line 4—4 of Figure 3, and

Figure 5 is a transverse sectional view taken on line 5—5 of Figure 3.

I have found that the apparatus hereinafter described, and its principle of application in accordance with my invention, could be satisfactorily employed in industrial processes requiring the use of superheated steam as a heat conveyor, heat transferor or humidifying agent for the drying and baking of cores, moulds, shapes and other forms of products, formed of sand, gypsum, plastics and other materials, where the elimination of varying shrinkages in the size and shape of the finished products, or the elimination of conditions arising during the drying and baking process tending to cause stresses and strains to develop in the materials being dried and baked, is an important element in the manufacturing process.

Reference is now had to the drawings, in which

2

like reference characters denote similar parts throughout the several views. As shown, there is an oven generally indicated at 2, mounted on legs 4, and including a housing having a bottom member or floor 6, side walls 12 and 14, front and rear end walls 8 and 10, and a top member or oven roof 16. These members form the oven itself, which has an oven chamber 18, one or more of the walls, such as 8 being removable in any suitable manner, such as by being pivoted or otherwise, to afford access to the inside of the chamber 18, where removable racks 20 (see Figure 1) may be installed for supporting small articles for treatment in the oven. Larger articles may be supported by removing one or more of the shelves of the racks, or by removing the racks entirely.

Supported in the oven housing is a heat generator housing generally indicated at 22, and having a chamber 24 formed by front and rear end walls 26 and 28, side walls 30 and 32, and top member 34, the side and end walls being supported upon the oven housing in any suitable manner, so that the top member 16 of the oven housing forms the floor of the heat generator chamber 24.

Communication between the heat generator chamber 24 and the oven chamber 18 is afforded by means of openings 36 and 38 formed in the oven roof member 16, near its rear and front ends respectively. A cylindrical tube or casing 40, forming a combustion chamber 42 is supported horizontally within the chamber 24, being spaced from the top, bottom and side inner wall surfaces thereof, and having its forward end 44 supported in contact with the inner surface of the front end wall 26 of the chamber 24. The rearward end 46 of the casing 40 is supported by a vertical member 48 which is spaced from the rearward wall 28 of the chamber 24. The inner walls of the rearward end of the chamber 42 are gradually reduced in inside diameter from location 50 to 52 as seen in Figure 3, the discharge outlet of the combustion chamber 42 being located at 52.

The vertical member 48 forms one wall of a fan housing within which is disposed a fan casting 54, with its intake in coincidence with the discharge outlet 52 of the combustion chamber 42. Its outlet pipe 56 leads downwardly into the hot gas passageway 36 formed in the member 16.

A fan 58 having blades 60 is mounted on a shaft 62 extending rearwardly out through rearward end wall 14, and journaled in appropriate bearings, not shown, the fan being driven by

means of a motor 64 connected to the shaft 62 by means of a belt 66 extending over pulleys carried on the motor and fan shafts respectively.

It is thus apparent that the rotation of the fan 58 will cause hot gases to be drawn through the combustion chamber 42, and circulated through the hot gas discharge duct 56 and the discharge opening 36, into the oven chamber 18, and thence upward through the forward intake opening 38, and thence through a duct 68 which leads from the opening 38 into the forward end of the combustion chamber 42.

A gas burner 70 having suitable air and gas inlets, is secured with its flame discharge opening 72 in registry with an axial opening 74 in the forward end wall of the combustion chamber 42, refractory material 76 being supported against the inner surface of the said forward wall, and having a flared axial bore 78 in the refractory material to allow passage of the flame 80 and hot gases into the combustion chamber. Flame sources other than a gas burner may also be used.

The greater part of the combustion chamber casing 40 is surrounded by a hollow annular water jacket casing 82 closed at both ends 84 and 86, and having a water chamber 88 for the reception of water 90 therein. Water is led into the water jacket through a water inlet pipe 92 which is connected to an outside source of water through a suitable valve. The water level in the water jacket is shown by means of a glass water level gauge 94 (see Figure 4) the upper and lower ends of which are connected into the interior of the water jacket by means of pipes 96 and 98.

A number of direct heating pipes 100 extend longitudinally within the fire chamber 42 so as to be in the path of and thus in direct contact with the flame and hot gases therewithin, the pipes 100 being connected at their ends 102 and 104 into the water jacket by means of appropriate elbows and fittings to permit water from the water jacket to circulate through the pipes 100. A safety valve, not shown, is connected to the upper end of the pipe 106 which communicates with the interior of the water jacket.

As a result of the hot flame and gases, steam is generated in the water jacket, and the steam is allowed to escape therefrom through a steam outlet pipe 108 connected at its upper end 110 into the water jacket, the pipe leading the steam past a valve 112 and through pipe 114 extending through an opening 116 in duct 68. As best seen in Figure 3, the steam is discharged from pipe 114 through a nozzle 118 which extends into the combustion chamber 42 so as to allow the steam to escape directly in the path of the flame and hot gases.

The steam thus collects additional heat as it passes through the combustion chamber from left to right as seen in Figure 3, and is then discharged through duct 56 into the oven chamber 18 under the influence of the blower fan 58.

As a result, there are obtained high humidity and comparatively high temperatures, which may, as desired, range from about 600 to 800 degrees Fahrenheit, without creating excess steam pressure, this being accomplished by the novel structure and method of superheating the steam by directly projecting it into the path of the hot flame and gases in the combustion chamber. Recirculation of the mixed hot gases and steam is accomplished under the influence of the fan 58 which circulates these products through the oven chamber and upwards through the duct 68 into

the combustion chamber, the circulatory flow continuing as long as the burner is in operation.

Suitable flue connections may be made as desired, to draw off hot gases and products of combustion, such as, for example, the one shown at 120 in Figures 2 and 3, with a damper inserted therein. The outer walls of the oven and the heat generator housing, together with the water jacket and the combustion casing, will preferably be insulated against the escape of heat. The usual controls for temperature, humidity, and other critical factors, will preferably be installed, although they are not illustrated in the drawings.

Although I have described a preferred embodiment of the invention in specific terms, it is to be understood that various changes may be made in size, shape, materials and arrangement without departing from the spirit and scope of the invention as claimed.

Having described my invention, what I claim and desire to secure by Letters Patent is:

1. A direct gas-fired oven heating device comprising a housing having a combustion chamber therein with inlet and outlet openings, and having an oven chamber with inlet and outlet openings, ducts connecting the outlet opening of the combustion chamber to the inlet opening of the oven chamber, and connecting the outlet opening of the oven chamber to the inlet opening of the combustion chamber, means for propagating flame and hot gases through said combustion chamber, water jacket means coaxing with said combustion chamber for generating steam from heat derived therefrom, duct means for conducting steam from said jacket into said combustion chamber, nozzle means for discharging said steam into said combustion chamber in the path of said flame, whereby said steam is intermixed therewith and superheated, and means for circulating said mixture of hot gases and superheated steam from said combustion chamber into said oven chamber, and back into said combustion chamber.

2. A direct gas-fired oven heating device comprising an oven housing having an oven chamber therein, a heat generator housing having a chamber therein, a hollow cylindrical combustion casing disposed in said heat generator housing chamber in spaced relation to the inner walls thereof, and having a cylindrical combustion chamber therein, a water jacket surrounding at least a portion of said combustion casing and having a plurality of water pipes connected at each end to said water jacket and extending longitudinally through a portion of said combustion chamber, a gas burner for discharging a flame directly into one end of said combustion chamber, a steam outlet pipe for conducting steam generated in said water jacket by said flame into the combustion chamber near the inlet for said flame whereby said steam is intermixed therewith and superheated, ducts interconnecting said combustion chamber and oven chamber, and a fan disposed in the path of the said mixture for circulating it from said combustion chamber into said oven chamber and back into said combustion chamber.

3. A direct gas-fired oven heating device comprising a heat generator housing having a chamber therein, a hollow cylindrical combustion casing disposed in said chamber in spaced relation to the inner walls thereof, and having a cylindrical combustion chamber therein, a water jacket surrounding at least a portion of said combustion casing, and having a plurality of water

pipes connected at each end into said water jacket and extending longitudinally through said combustion chamber, a burner for discharging a hot flame into said combustion chamber whereby steam is generated in said water jacket, a steam outlet pipe for conducting said steam into said combustion chamber, a nozzle on said pipe for discharging said steam into the combustion chamber directly in the path of said flame, whereby the steam is intermixed therewith and superheated, and a fan rotatable in said housing in the path of said mixture for drawing the same through the combustion chamber and discharging it from said housing, said housing having inlet and outlet openings connectable with apparatus requiring moist heat whereby upon such interconnection the heated mixture may be cir-

culated between said combustion chamber and said apparatus.
